FIG. 1.

FIG. 2.

FIG. 3.

INVENTOR.
BY *E. Colman Beebe*
Gardiner W. Peacock, Attorney

UNITED STATES PATENT OFFICE

135,791

DESIGN FOR A SHOE SOLE

E. Colman Beebe, Nashua, N. H., assignor to Beebe Brothers Rubber Company, Nashua, N. H., a corporation of New Hampshire

Application April 16, 1943, Serial No. 109,985

Term of patent 14 years

To all whom it may concern:

Be it known that I, E. Colman Beebe, a citizen of the United States of America, residing at Nashua, in the county of Hillsborough and State of New Hampshire, have invented a new, original, and ornamental Design for a Shoe Sole, of which the following is a specification, reference being had to the accompanying drawing, forming part thereof.

Fig. 1 is a bottom plan view of a shoe sole showing my new design;

Fig. 2 is a top plan view thereof; and

Fig. 3 is a side elevational view thereof.

I claim:

The ornamental design for a shoe sole, as shown.

E. COLEMAN BEEBE.
